EXCAVATING AND LOAD HANDLING
MACHINE

Roy H. Zeilman, Lorain, Ohio, assignor to Thew
Shovel Company, Lorain, Ohio, a corporation of
Ohio

Application September 8, 1941, Serial No. 409,915

10 Claims. (Cl. 212—69)

My invention relates to excavating and load handling machines of the vehicular type comprising a base and a rotatable superstructure mounted thereon, and relates more particularly to improvements in the design and arrangement of the base and the mounting thereon of the superstructure.

An object of the invention is to provide, for power operated load handling and excavating machines of the type described, an improved construction whereby the weight of the superstructure may be utilized in an improved manner for counterbalancing purposes.

Another object of my invention is to provide, for power operated load handling and excavating machines of the type described, an improved positioning of the operator's cab.

Another object of my invention is to provide, for power operated load handling and excavating machines of the type referred to, an improved mounting therefor whereby either a crane boom or shovel boom may interchangeably be accommodated and their respective weights adjusted and properly counterbalanced.

Another object of my invention is to provide such improved mounting for the superstructure of load handling and excavating machines of the type referred to as to afford a better balance and better steering action when said machine is travelling.

A further object of my invention is to provide such improved mounting for the superstructure adapted to be associated with a load handling and excavating machine of my invention as to afford the most efficient position when travelling or working of the superstructure associated therewith.

Other objects of my invention and the invention itself will be more clearly understood by reference to the accompanying drawings illustrating an embodiment of my invention in which drawings:

Figure 1 is a top plan view partially in section looking down upon the improved mounting base of my invention and showing the respective positions of the cab, the engine and motor housing and associated parts;

Fig. 2 is a section taken from the line 2—2 of Fig. 1;

Fig. 3 is a perspective view of a complete truck showing a crane associated therewith;

Fig. 4 is a perspective view of the complete truck of my invention showing a power shovel associated therewith;

Fig. 5 is an enlarged side elevational view of the 55

crane of my invention showing it in operative use in contrast to Fig. 3 wherein the crane is shown in travelling position; and

Fig. 6 is a side elevational view of the truck of my invention showing a power shovel associated therewith, said power shovel being in a position of use, as contrasted with Fig. 4 showing the power shovel in its travelling position.

Heretofore the booms of cranes and power shovels and the like, when in working or travelling position, have had to project upwardly at a considerable angle so as to clear the driver's cab. The overall height has thus been necessarily much greater than was desirable, limiting the clearance with which the vehicle could pass beneath an overhead structure and impairing the equilibrium by placing the center of gravity of the vehicle as a whole too high above the ground. In the machine of the present invention, this condition has been improved.

In Figs. 1, 3 and 4, the cab of the truck is shown disposed forwardly and at the left hand side thereof, the motor being centrally disposed and a relatively wide portion to the right of the truck being reserved as a platform to accommodate a crew and for convenience in servicing the motor. The cab, therefore, is positioned well to one side of the center line of the truck and the boom 20 of a crane or the like or the boom 30 and dipper stick 31 of a power shovel may be conveniently lowered beside it to reduce the overall height and the elevation of the center of gravity. Figs. 3 and 4 illustrate the travelling positions of a crane and a power shovel respectively.

In Fig. 1, the cab is designated at 1, the motor at 2, and the platform at 3 and a wall or railing for the platform at 3'. Rearwardly of the cab, motor and platform portion of the truck, which is the forward or leading portion thereof, the truck is provided with a chassis frame 4 and a pair of tandem driving wheels 4'. A turntable 6 is adapted to be mounted upon the chassis and the particular superstructure desired is mounted upon the turntable.

A special mounting plate 5, secured to the chassis 4, is employed for the turntable 6, to which I have previously referred, and such special mounting 5 consists in a generally rectangularly shaped metal plate 7 having convex end portions 8—9. The turntable 6 is adapted to be bolted to the plate 7 in either of two positions and the plate, therefore, is provided with two sets of bolt apertures. As illustrated in Fig. 1, each set may consist of four groups, those for the forward position of the turntable being designated by x and those

for the rearward position by y . The turntable 6 is provided with a similar set of apertures, as illustrated in Fig. 2, which may therefore be placed in registration with either of the sets x or y and the turntable thus mounted for either crane or shovel operation, as will be later more fully described.

Reference should be had to Fig. 2 herein where-
in the turntable 6 is shown mounted upon the
mounting plate 7 in its rearmost position, as illus-
trated in Fig. 6 of the drawings. In this pos-
ition, the bolts 13 are placed in the rearmost aper-
tures y and, when so mounted, the turntable
kingpin 10 is disposed within a clearance open-
ing 11 provided in the turntable mounting plate
7. When the turntable 6 is mounted upon the
mounting plate 7 in its foremost position, as
shown in Fig. 5, the bolts 13, which were placed
in the apertures y in the rearmost position, are
moved forwardly and engage the apertures x and
the kingpin is then disposed within a suitable
clearance opening 12 of the mounting plate.

The superstructure 14, in accordance with the
usual practice, is mounted by means of tapered
rollers 15 upon a trackway 16 of the turntable 6
which, in turn, is secured by means of the bolts
13 to the turntable mounting plate 7 and the
kingpin 10 rotatably secures said superstructure
14 and said turntable 6 together.

In adapting the excavating and load handling
machine of my invention, with optional place-
ment of a crane or shovel boom, both for travel-
ling and operating positions, it will be noted
that since the crane boom is lighter than the
combined shovel boom, dipper stick and shovel,
the forward mounting for the crane is preferred,
particularly when in travelling, in order to secure
sufficient weight on the front wheels to obtain
good steering action.

The turntable is however mounted rearwardly
when associated with the shovel boom to enable
the shovel to begin a cut close to the vehicle
and rearwardly thereof and since the shovel
boom is heavier than the crane boom, sufficient
weight is nevertheless mounted on the front
steering wheels, in travelling, despite this rear-
most mounting of the shovel boom.

Although I have chosen to illustrate my in-
vention as applied to power shovels and cranes,
it is to be understood that the same is equally
adaptable to any load handling or excavating
machine rotatable upon a base, such as a clam
shell back digger as well as a crane or a shovel
and that numerous and extensive departures
may be made from the embodiment herein illus-
trated and described without, however, depart-
ing from the spirit of my invention and the
scope of the appended claims.

I claim:

1. A mounting plate for excavating and load
handling machines of the type comprising a
turntable and a superstructure mounted thereon,
said turntable mounting comprising a generally
rectangular metal plate having convex end por-
tions, said plate being provided with two sets of
bolt apertures and clearance openings, the turn-
table being provided with an aligned set of
apertures, said turntable apertures being placed
in registry with either set of apertures and the
turntable kingpin being adapted to be disposed
within an associated clearance opening.

2. In an excavating and load handling ma-
chine, a superstructure mounted upon a turn-
table, a support for said turntable, said support
comprising a rectangular frame, a mounting
plate secured thereto, said mounting plate com-

prising a plurality of apertures and clearance
openings whereby a superstructure adapted to
be rotatably mounted upon said turntable and
said turntable is adapted to be positioned for-
wardly or rearwardly with respect to said frame.

3. In an excavating and load handling ma-
chine, a superstructure mounted upon a turn-
table, a support for said turntable comprising
mounting means disposed forwardly and rear-
wardly of said mounting plate whereby various
types of superstructures may be associated there-
with, said superstructure and turntable being
locked into optional position with said mounting
plate either forwardly or rearwardly thereof.

4. An excavating and load handling machine
comprising a truck frame, a turntable adjustably
mounted thereon, a superstructure mounted
upon said turntable, said superstructure and
turntable being adapted to have longitudinally
movable mounting with respect to said truck
frame.

5. In an excavating and load handling ma-
chine, a truck chassis having mounted thereon
a turntable upon which a superstructure is
erected, a mounting for said turntable comprising
a plate having a plurality of perforations
disposed therein, means adapted to be projected
through said perforations and to rigidly secure
said turntable to said mounting plate, said lat-
ter means being adapted to be optionally posi-
tioned within certain of said perforations to se-
cure different relative positions of said turntable
and the superstructure erected thereon with re-
spect to the truck chassis.

6. In an excavating and load handling ma-
chine, a truck chassis having mounted thereon
a turntable upon which a superstructure is
erected, a mounting for said turntable comprising
a plate having a plurality of perforations
disposed therein, said perforations being longi-
tudinally disposed therein, securing means
adapted to be associated with said turntable and
to be optionally positioned within certain of said
longitudinally disposed perforations whereby said
turntable may be secured to said mounting plate
in a desired position with respect to the truck
chassis.

7. A mounting plate for excavating and load
handling machines of the type comprising a
turntable and a superstructure mounted thereon,
said turntable mounting comprising a generally
rectangular metal plate having convex end por-
tions, said plate being provided with two sets of
bolt apertures and clearance openings, the turn-
table being provided with an aligned set of
apertures, said turntable apertures being placed
in registry with either set of apertures provided
in said turntable mounting plate, bolts adapted
to be projected through said aligned apertures
securing said turntable and said mounting plate
together and a turntable kingpin adapted to be
disposed within an associated clearance opening.

8. A mounting plate for excavating and load
handling machines of the type comprising a
turntable and a superstructure mounted thereon,
said turntable mounting comprising a generally
elongated rectangular metal plate, said plate be-
ing provided with two longitudinally extending
sets of bolt apertures and clearance openings,
the turntable being provided with a set of aper-
tures adapted to be placed in registry with
either set of plate apertures, means to secure
said turntable and plate together, said means
being projected through a selected set of aligned
apertures and the turntable kingpin adapted for

disposition within either of a pair of longitudinally spaced clearance openings of said plate.

9. A mounting plate for excavating and load handling machines of the type comprising a turntable and a superstructure mounted thereon, said turntable mounting comprising plate means, a plurality of sets of turntable connecting means on said plate, the connecting means of each set being longitudinally displaced relative to the means of the other set, each of said sets being adapted to rigidly connect said turntable to the plate in relatively different longitudinal positions on the frame.

10. In an excavating and load handling machine of the type comprising a superstructure mounted thereon, a support for said superstructure, said support comprising a plurality of sets of superstructure connecting means, the means of each set being longitudinally displaced relative to the means of the other sets, each of said sets being adapted to securely connect the superstructure to the support whereby the superstructure is adapted to have longitudinally adjusted position with respect to said support.

ROY H. ZEILMAN.
